(57) **CLAIM**

The ornamental design for a toddler bottle with top and cap, as shown and described.

DESCRIPTION

FIG. 1 is a top front perspective view of our new design for a toddler bottle with top and cap, shown with the cap in an open position;

FIG. 2 is a top rear perspective view thereof with the cap in an open position;

FIG. 3 is a top front perspective view thereof with the cap in a closed position;

FIG. 4 is a top rear perspective view thereof with the cap in a closed position;

FIG. 5 is a bottom rear perspective view thereof with the cap in a closed position;

FIG. 6 is a front view thereof with the cap in a closed position;

FIG. 7 is a rear view thereof with the cap in a closed position;

FIG. 8 is a left side view thereof with the cap in a closed position;

FIG. 9 is a right side view thereof with the cap in a closed position;

FIG. 10 is a top view thereof with the cap in a closed position; and,

FIG. 11 is a bottom view thereof with the cap in a closed position.

The broken lines shown are environmental only and form no part of the claimed design.
